CHARLES MELLEM PERRIER, OF BROCKTON, MASSACHUSETTS.

LADDER ATTACHMENT.

1,414,893.

Specification of Letters Patent. Patented May 2, 1922.

Application filed October 19, 1920. Serial No. 417,910.

To all whom it may concern:

Be it known that I, CHARLES MELLEM PERRIER, a citizen of the United States, residing at Brockton, in the county of Plymouth, in the State of Massachusetts, have invented a new and useful Ladder Attachment, of which the following is a specification.

This invention relates to that class of ladder attachments adapted to prevent slipping of the ladder when placed against a wall or other support.

The general objects of the invention are to provide an attachment of this character which is readily applied to all makes of ladders without materially changing the construction of the same, which is strong yet simple, and which has a hook held locked or secured in place when in extended position.

The invention will be best understood from a consideration of the following detailed description taken in connection with the accompanying drawing forming part of this specification, with the understanding, however, that the invention is not confined to any strict conformity with the showing in the drawing, but may be changed and modified so long as such changes and modifications mark no material departure from the salient features of the invention as expressed in the appended claims.

In the drawing:—

Fig. 1 is an elevation of a fragment of a ladder with an embodiment of the invention in place, showing the hook portion extended and caught over a cornice, the latter being indicated in dotted lines.

Fig. 2 is an enlarged elevation of the same, showing the hook in retracted position.

Fig. 3 is a side elevation of the showing of Fig. 2.

Fig. 4 is a detail fragmentary view partly in section, showing the locking means for the hook.

The numeral 5 designates the side of a ladder, to which a plate 6 is secured. There should be one of these plates on each leg of the ladder near the upper end thereof. Each plate constitutes a base for the ladder attachment, which forms the subject of the present invention. The plate 6 has an integral expansion or prolongation 7 which is bent over and returned parallel to the plate, though slightly spaced therefrom. A hook 8 is mounted between the extension 7 and

the plate 6, a screw or the like 9 passing between the parts 6 and 7 and holding the extension 7 in the proper position. The hook 8 is flat on both sides so as to swing readily between the extension 7 and plate 6. 60 This hook has inturned ends in the form of a C and is adapted to be locked to the position shown in Fig. 1 by means of a spring catch 10. One end of the spring 10 is made fast to the plate by a rivet or the like 65 11. The other end of the spring is bent inwardly, as indicated at 12, and enters through a slot 13 in the plate 6, into a recess 14 cut in the leg of the ladder. The spring near the bent portion 12 curves outwardly away from the ladder as seen in Figs. 3 and 4. When the hook 8 is moved from the position of Fig. 2, to that of Fig. 1, it first depresses the free end of the spring catch 10 and thereafter snaps in place below 70 said end, whereupon the spring will raise and will prevent the hook from swinging along the plate 6. The locking position is best shown in Fig. 4.

The hook 8 is especially designed to engage over roof projections, cornices, gutters or the like, in the manner shown in Fig. 1; thus the ladder will not slip even though the ground support be a dangerous one. In applying the ladder to a building, the 80 lower free end of the hook-like member 8, which projects beyond the ladder leg as shown in Fig. 2, is engaged beneath the cornice or spout 15 of the building, and as the ladder is shoved upwardly, it will cause 90 the hook-like member to tilt upon its pivot 9, forcing the lower free end of the member 8 inwardly, while the upper free end is forced outwardly and downwardly upon the upper edge of the cornice 15. Thus it will 95 be seen that the hook 8 is automatically operated when the ladder is applied to the building. When removing the ladder, the ladder itself is raised sufficiently upward and outwardly to release the hook 8 from its engagement with the cornice 15.

The present ladder attachment occupies an extremely small space because of the fact that the plate 6 with its extension 7, spring 10 and the hook 8, are all formed of flat metal. The attachment adds very little to the width of the leg 5, as is seen in Fig. 3, and thus it is not in the way of such other attachments as it may be desired to employ. The construction, while of light weight and 110

compact, is easily made sufficiently strong to bear the heaviest load for which the ladder is designed.

What is claimed is:

- 5 1. The combination with a ladder leg and a guard secured thereto for automatically gripping a fixed part of a building, said guard comprising a plate, a hook-like member pivoted to the plate having inturned ends with one end normally projecting beyond the ladder leg, whereby as the ladder is applied to a building said projecting end is moved inwardly while the opposite end is forced outwardly, automatically gripping a fixed part of the building, and a catch engageable with said member and locking the same against retraction.
- 10 2. The combination with a ladder leg and a guard secured thereto for automatically gripping a fixed part of a building when the ladder is applied, said guard comprising a flat plate secured at one end of the ladder leg upon the outer face thereof, said plate having an integral expansion spaced from and bent into parallelism therewith, a securing element mounted between the extension and plate and holding the former in position, a hook-like member mounted between the extension and plate and held by the securing element, one end of said hook-like member normally projecting beyond the ladder leg and adapted to be engaged by a

fixed part of the building and moved inwardly between the plate and its extension as the ladder is positioned, the other end 35 of said element being simultaneously moved outwardly into gripping relation to said fixed part, and a spring catch engageable with said hook-like member on completion of said movement to lock the same against 40 retraction.

3. The combination with a ladder leg and a guard secured thereto for automatically gripping a fixed part of the building when the ladder is applied, said guard comprising 45 a flat plate secured at one end of the ladder, a hook-like member mounted on a pivot on the plate, said member being C-shaped, one of the ends of said hook-like member being adapted to be always projected beyond the plate and the ladder leg, and a spring catch adapted to engage the edge of the hook-like member near one end and hold the ladder with the other end extended, the lower free end of the hook-like member 55 being adapted to be operated when the ladder is applied to a building so as to force the upper free end of the member into engagement with the fixed support.

In testimony that I claim the foregoing 60 as my own, I have hereto affixed my signature.

CHAS. MELLEM PERRIER.
